COVER FOR ELECTRIC TOASTER

Bess Kaye, New York, N. Y.

Application April 30, 1956, Serial No. 41,275

Term of patent 3½ years

(Cl. D58—2)

Fig. 1

Fig. 2

Fig. 1 is a front perspective view of a cover for electric toaster, showing my new design; and

Fig. 2 is a rear perspective view thereof, upside down.

The characteristic feature of my design for the cover disclosed resides in the pattern represented in full lines on the side thereof as shown.

I claim:

The ornamental design for a cover for electric toaster, as shown and described.
